HIDALGO MOYA, OF NORTH EVINGTON, LEICESTER, ENGLAND, ASSIGNOR TO IMPERIAL TYPEWRITER COMPANY, LIMITED, OF LEICESTER, ENGLAND.

TYPE-WRITER OR THE LIKE.

1,183,662.

Specification of Letters Patent. Patented May 16, 1916.

Application filed October 30, 1915. Serial No. 58,784.

To all whom it may concern:

Be it known that J. HIDALGO MOYA, a citizen of the United States of America, residing at North Evington, in Leicester, England, have invented certain new and useful Improvements in Type-Writers or the like, of which the following is a specification.

This invention is for improvements in or relating to typewriters or the like and has 10 for its object to provide a compact key-lever mechanism, and is particularly applicable to the well-known Imperial machines. In these machines as at present made, the frame carrying the key-levers and type-bars can 15 be lifted bodily away for the purpose of substituting another having different characters upon it or for renewal purposes, and the key-levers are splayed out from the center of the machine so that they provide a 20 curved key-board. By means of the present invention a straight key-board is obtained and the key-lever mechanism is still of such character that it can all be mounted on the movable frame to come away with the type- 25 bars.

According to this invention, each type-bar is approximately vertical when in the position of rest, the corresponding key-lever is situated wholly in front of the type-bar, 30 upper and lower forwardly directed approximately parallel levers are pivotally connected at one end to the key-lever and at the other end to a support of the mechanism, an arm is rigidly connected to one of 35 these levers, the length of the said arm being greater than that of the lever, and a link which directly connects the said arm to the type-bar. The situation of these parts gives a compact arrangement of key-levers, type- 40 bars and the intervening connecting elements, and reduces the number of parts ordinarily employed between the key-levers and type-bars.

In the accompanying drawings which 45 illustrate one method of carrying out this invention:—Figure 1 shows diagrammatically in side elevation a key-lever with its associated parts; Fig. 2 is a front view showing two of the sub-levers, and Fig. 3 50 is a plan showing two of the lower links for guiding the key-levers.

The same letters indicate the same parts throughout the drawings.

Each key-lever of the machine has a downwardly and forwardly sloping portion 55 A which carries a vertical stem A¹ on which is secured a key A². That end of the key-lever which is nearest the type-bars extends vertically upward at A³ and is pivoted at A⁴ to one arm B of a sub-lever. The sub- 60 levers are pivoted on a horizontal rod C which lies close behind the type-bars D when these are in the position of rest. Each sub-lever is a bell-crank lever, whereof the arm B, already referred to, is forwardly 65 and upwardly inclined when the parts are in the position of rest, in which position they are shown in full lines in Fig. 1, and a second arm B¹ which is downwardly and forwardly inclined and is longer than the 70 arm B. The arm B¹ is operatively connected with the type-bar D by a wire link D¹.

The forward end of each key-lever is pivoted at A⁵ to one end of a lever E whose other end is pivoted to a horizontal rod F. 75 Beneath the lever E is a spring E¹, one end of which bears against the lever, the other end being supported in a socket E². The rods C and F are mounted in any convenient way on the frame for the key-lever 80 mechanism, which frame in itself constitutes no part of the present invention and therefore need not be described, and similarly the sockets E² are carried by some part of the frame.

It will be seen that with the arrangement shown the key-lever is suspended from its supporting frame by the levers E and B and kept normally in the raised position by the spring E¹. When the key A² is depressed, 90 the whole key-lever moves in such direction as to be displaced bodily approximately parallel to itself, the sub-lever being swung about the rod C so that it operates the type-bar to bring it to the striking position. The 95 positions taken by the various parts when the type-bar is in the full striking position is indicated by chain-lines in Fig. 1.

By this arrangement of key-lever mechanism a straight key-board is obtainable, the 100 lines of the keys being parallel to the rods C and F, and although the whole of each key-lever is situated in front of its type-bar and is of such length that the key-board is approximately the same distance away from 105 the type-bars as has been the case with pre-

viously made Imperial machines in which the key-levers directly engaged the type-bars, yet the key as it is depressed does not tilt unpleasantly owing to the parallel levers 5 B and E upon which it swings, although the space occupied by the lever from front to back is little more than equal to the depth of the key-board. If desired, the mechanism could be such that the key has no tilting 10 movement, that is to say, the arm B and lever E could be made equal in length so that a perfectly parallel movement would be imparted to the key-lever, but the tilt given by the mechanism, as shown, is very 15 slight.

Each sub-lever B, B¹ is conveniently provided with an ear-piece B² which is first bent over parallel to the rod C and then bent back to the rod, as shown at B³ Fig. 2, so that the 20 rod can pass through the lever and the portion B³ of the ear-piece whereby a wide bearing is given to the sub-lever; the ear-piece of one lever moreover may be made to serve as the spacing means for properly distancing 25 the next lever, as shown in Fig. 2. The levers E may similarly be provided with wide bearings by making them approximately U-shaped and widening out the bend of the U as shown at E³, Fig. 3, so that this 30 widened portion affords a double bearing on the rod F and may serve as distancing means between one lever and the next.

All the key-levers are of such length that they can be carried by the levers B and E 35 which are spaced the same distance apart for all of the levers, but the stem A¹ may be placed either in the position shown in full lines in Fig. 1, or in one or other of the 40 positions indicated by dotted lines in the same figure according to the bank of keys to which the lever is to be allotted. The keys can thus all be stamped out alike and two of the stems A¹ sheared off when applying it to the machine and also the end of the 45 lever beyond the point of pivoting A⁵ may be sheared off when such lever is not to be used for the most forward bank of keys.

Each type-bar has a projection D² near its base which co-operates with a bail G, but 50 this arrangement of bail and means for operating it is known and constitutes no part of the present invention.

The type-bars are of course arranged in the arc of a circle as is usual practice, which 55 arrangement is permitted notwithstanding the fact that the sub-levers are arranged along a straight line, as the links D¹ allow the type-bars to be set at an angle to the sub-levers without interfering with the 60 proper operation of the former by the latter.

This key-lever mechanism affords a remarkably light touch and as the movement is a parallel one, there is no difference of 65 touch experienced in operating the front or

the rearmost bank of keys, as the leverage is the same for both.

What I claim as my invention and desire to secure by Letters Patent is:—

1. In a typewriter the combination of, 70 a type-bar which is approximately vertical when in the position of rest, a key-lever in front of the type-bar, upper and lower forwardly directed approximately parallel levers pivotally connected at one end to the 75 key-lever and at the other end to a support of the mechanism, an arm rigidly connected to one of these levers the length of the said arm being greater than that of the lever, and a link connected to said arm and to the 80 type-bar, substantially as set forth.

2. In a typewriter the combination of, a 85 type-bar which is approximately vertical when in the position of rest, a key-lever in front of the type-bar, upper and lower forwardly directed approximately parallel levers pivotally connected at one end to the key-lever and at the other end to a support of the mechanism, a pendent arm rigidly 90 connected to one of these levers, said arm being of greater length than that of the lever, and a link pivotally connected to the free end of the arm and the type-bar near the pivot point of the latter, substantially as set forth.

3. In a typewriter the combination of, a type-bar which is approximately vertical when in the position of rest, a key-lever in front of the type-bar, upper and lower forwardly directed approximately parallel levers pivotally connected at one end to the key-lever and at the other end to a support of the mechanism, the pivotal connection to the support for the upper lever being just 100 in front of the type-bar when in its position of rest, a depending arm rigidly connected to the upper lever, which arm is of greater length than the lever, and a link connected to the free end of the arm and the type-bar at a point near the pivotal axis of the latter, substantially as set forth.

4. In a typewriter, the combination of, a type-bar which is approximately vertical when in the position of rest, a key-lever in front of the type-bar, said key-lever having a downwardly and forwardly sloping portion approximately parallel to the slope of banks of keys, and having key-stems thereon for all three banks so that those which are not required can be cut off, upper and lower forwardly directed approximately parallel levers pivotally connected at one end to the key-lever and at the other end to a support of the mechanism, the pivotal connection to the support for the upper lever being just in front of the type-bar when this 110 is in its position of rest, a depending arm rigidly connected to the said upper lever which arm is of greater length than the lever, and a link connected to the free end of the 115

the arm and the type-bar at a point near the pivotal axis of the latter, substantially as set forth.

5. In a typewriter the combination of, a type-bar which is approximately vertical when in the position of rest, a key-lever in front of the type-bar having a downwardly and forwardly sloping portion approximately parallel to the slope of the banks of keys, upper and lower forwardly directed approximately parallel levers pivotally connected at one end to the key-lever and at the other end to a support for the mechanism, the pivotal connection to the support for the upper lever being just in front of the type-bar when in its position of rest, the pivotal connection for the lower lever being in front thereof, a depending arm rigidly connected to the said upper lever which arm is of greater length than the lever, and a link connected to the free end of this arm and the type-bar at a point near the pivotal axis of the latter, substantially as set forth.

6. In a typewriter the combination of, a type-bar which is approximately vertical when in the position of rest, a key-lever in front of the type-bar and having a forwardly and downwardly sloping portion which is approximately parallel to the slope of the banks of keys, the upper end of such sloping portion having a vertical extension, upper and lower forwardly-directed approximately parallel levers pivotally connected at one end to the key-lever and at the other end to a support of the mechanism the pivotal connection of the upper lever to its support being just in front of the type-bar when this is in the position of rest and its connection to the key-lever being at the top of the vertically extending portion of the key-lever, the pivotal connection of the lower lever to its support being in front of the corresponding connection for the upper lever, the lower lever being pivoted to the sloping portion of the key-lever, a depending arm rigidly connected to the said upper lever which arm is of greater length than the lever, and a link connected to the free end of this arm and the type-bar at a point near the pivotal axis of the latter, substantially as set forth.

7. In a typewriter the combination of, a type-bar which is approximately vertical when in the position of rest, a key-lever in front of the type-bar and having a forwardly and downwardly sloping portion which is parallel to the slope of the banks of keys, the upper end of such sloping portion having a vertical extension, upper and lower forwardly directed approximately parallel levers pivotally connected at one end to the key-lever and at the other end to a support of the mechanism, the pivotal connection of the upper lever to its support being just in front of the type-bar when

this is in the position of rest and its connection to the key-lever being at the top of the vertically-extending portion of the key-lever, the pivotal connection of the lower lever to its support being in front of the corresponding connection for the upper lever and approximately on the same level as the pivotal axis of the type-bar, the said lower lever being pivoted to the sloping portion of the key-lever, a depending arm rigidly connected to the said upper lever which arm is of greater length than the lever, and a link connected to the free end of said arm and the type-bar at a point near the pivotal axis of the latter, substantially as set forth.

8. In a typewriter the combination of, a plurality of type-bars, a plurality of key-levers therefor the whole of each key-lever being situated in front of its type-bar and having a part which slopes downwardly and forwardly corresponding to the slope of the banks of keys, a plurality of bell-crank sub-levers one arm of each of which is operatively connected to a type-bar and the other arm is pivoted to a corresponding key-lever at a point toward one of its ends, and a lever below each sub-lever and parallel to the arm thereof which is pivoted to a key-lever but situated at a different level and pivoted at one end to a support of the mechanism and at the other end to a key-lever at a point near the opposite end to that at which the sub-lever arm already referred to is pivoted, the said sub-levers being arranged to pivot about a common axis and the levers below the sub-levers being arranged to pivot about a common axis for these levers parallel to the axis for the sub-levers, each key-lever moreover having three vertical key-carrying stems projecting from its sloping face any two of which are cut off before the lever is mounted in the machine so that the same levers can be used for any bank of keys in the machine by cutting off the key-carrying stems which are not required for that bank, substantially as set forth.

9. In a typewriter the combination of, a type-bar, a bell-crank sub-lever pivoted at a point which lies close to but in front of the type-bar when the latter is in the position of rest, one of the arms of the said sub-lever being then in such position that it projects forwardly of the machine, means operatively connecting the other arm with the type-bar, a key-lever having a downwardly and forwardly sloping portion the slope of which corresponds to the slope of the bank of keys, the upper end of the said key-lever being pivoted to the forwardly-projecting arm of the sub-lever, and a lever mounted below the sub-lever and parallel thereto, said lever being pivoted at one end to a support of the mechanism and at the

other end to the key-lever so that when the key is struck the key-lever is guided by the said sub-lever arm and the lever in a path which is downward and approximately parallel to itself, substantially as set forth.

10. In a typewriter the combination of, a type-bar, a bell crank sub-lever pivoted at a point which lies close to the ends of the type-bar when in the position of rest, one of the arms of the said sub-lever being then in such position that it projects forwardly with relation to the machine, means operatively connecting the other arm with the type-bar, a key-lever having a downwardly and forwardly sloping portion the slope of which corresponds to the slope of the banks of keys, the upper end of the said key-lever being pivoted to the forwardly-projecting

arm of the sub-lever, and a lever mounted below the sub-lever and parallel thereto, 20 said lever being pivoted at one end to a support of the mechanism and at the other end to the key-lever, the proportion and arrangement of the lever relatively to the sub-lever arm being such that when the key 25 is struck the key-lever is carried downward and slightly backward by an approximately parallel movement, substantially as and for the purpose set forth.

In testimony whereof I have signed my 30 name to this specification in the presence of two subscribing witnesses.
